FLUID PUMP

James J. Pelouch, Cleveland, Ohio, assignor to
The United States Air Compressor Company, a
corporation of Ohio

Original application May 6, 1938, Serial No.
206,409. Divided and this application October
16, 1941, Serial No. 415,290

10 Claims. (Cl. 103—203)

My invention relates to pumping devices and more particularly to the releasing of entrapped air therefrom liberated by the substance being pumped.

An object of my invention is to provide a pumping device adapted to be mounted over a container and having an end which may be inserted through an opening in the container for pumping fluid therefrom.

Another object is to provide a pumping device for entrapping air liberated from the fluid in the device and for discharging the entrapped air to provide a flow of fluid substantially free of air.

Another object is to provide a valve arrangement for venting entrapped air from a pumping device without discharging fluid through the vent.

Another object is to provide a valve arrangement responsive to the operating position of a pumping device for controlling an air vent for releasing entrapped air from the pump.

A still further object is to provide an improved pumping device efficient in operation and economical in maintenance.

Other objects and a fuller understanding of my invention may be had by referring to the following description and claims, taken in conjunction with the accompanying drawing, in which:

Figures 1 and 2 are cross-sectional views taken lengthwise and vertically along the longitudinal center of a pump embodying the features of my invention, Figure 1 showing the upper portion of the pump and Figure 2 the lower portion thereof, the two figures comprising the complete pump.

My pump is particularly adapted to be mounted to or mounted over a fluid container having an opening in the top thereof so that the lower end of the pump extends down into the container for the pumping of the fluid therefrom. This method of pumping fluid is especially used when grease or other lubricating fluid is to be withdrawn from the fluid container and applied to the parts to be lubricated, the fluid after leaving the pumping device passing through a hose attached thereto having a suitable nozzle attached to the end thereof. The pump may be operated by a fluid motor such, for example, as shown in my Patent No. 2,268,898, issued January 6, 1942, for Fluid motor of which this application is a division. In Figure 1 of the drawing, the reference character 16 represents the side walls of the cylinder of the fluid motor and the reference character 125 represents a casing mem-

ber constituting one end of the cylinder. The piston which is reciprocally mounted within the cylinder wall 16 is adapted to operate the pump plunger 19. The casing member 125 is adapted to be mounted to a suitable support for supporting the top in proper position relative to the fluid container so that the pump is directed downwardly into the container. A cylindrical metal cover 17 is secured by suitable means to the cylinder wall 16 to provide good appearing and round outside surface to the fluid motor.

The plunger 19 extends down through the central bore of the casing member 125 and is secured to a lower plunger 134 by the threaded connection 135 and the cross-pin 136, so that the plunger 134 reciprocates as a unit with the plunger 19.

A fluid chamber member 133 is positioned below and secured by bolts or other suitable means to the casing member 125. The casing member 125 and the fluid chamber member 133 together form an enclosure within which there is a fluid chamber. Threadably secured to the lower end of the chamber member 133 is a pump cylinder 152 and threadably secured to the lower end of the pump cylinder 152 is an extension portion 153.

Threadably secured upon the lower end of the plunger 134 is a valve head 158 so that the valve head 158 reciprocates with the plunger 134. A cage member 159 around which the screen 160 is mounted is carried by the head 158 at the lower end. The screen 160 prevents foreign matter from being drawn in through the pump cylinder into the pumping mechanism. The cage member 159 carried by the head 158 is secured thereto at its lower end by the cross pin 161 so that the cage member 159 slidably fitting within the cylinder 152 moves up and down with the head 158 and the plunger 134. There is a movable piston 154 through which the plunger 134 extends and the piston 154 slides up and down within the cylinder 152. The movable piston 154 has a plurality of openings 151 providing communication between the upper side of the piston 154 and the lower side to permit fluid to flow through the piston 154. There is a shoulder 155 on the piston 154 which is adapted to engage the shoulder 155 upon the plunger 134. The piston 154 is also adapted to engage the valve head 158 at the junction 157. Therefore the valve head 158 engages and carries upwardly the piston 154. The valve head 158 and the piston 154 meeting at the junction 157 thereby close communication through the openings 151 sealing the space

above the piston 154 from the space below. Upon downward movement, however, the shoulder 155 of the plunger 134 engages the shoulder 156 and thereby carries the piston 154 downwardly. There is then a space between the piston 154 and valve head 158 upon downward movement, with the head 158 and the piston 154 separated at the junction point 157, so that there is communication established through the openings 151 to both sides of the piston 154. Therefore, upon downward movement of the plunger 134, the piston 154, and the head 158 are merely displaced in the fluid within the cylinder 152. Upon upward movement of the plunger 134 the openings 151 are thereby closed at the junction 157 and a sucking or pumping action is obtained by the raising action of the piston 154 up through the cylinder 152 which draws fluid up into the pump cylinder from the fluid container.

A check valve 162 is positioned at the inlet opening 164 at the bottom of the pump housing. The check valve 162 permits fluids to be drawn up into the pump housing upon the raising of the piston 154 and also acts to entrap fluid within the pump cylinder upon downward movement of the plunger 134. A coil spring 163 carried by the extension portion 153 is provided to bias the check valve 153 in its closed position except when there is a sucking action by the pump.

Mounted within one wall of the chamber member 133 and approximately at its upper end is an air outlet plug 141, which extends through the wall of the chamber member 133 and is secured thereto by bolts or, other suitable means. An air outlet conduit 140 extends through the outlet plug 141 so as to provide communication between the inside of the chamber member 133 and the outside atmosphere.

To provide valve means for opening and closing the air outlet conduit 140, there is provided a valve arrangement 139 which is operated by the reciprocal movement of the plunger 134 through a sleeve 137 which surrounds and loosely fits about the plunger 134 so that the plunger 134 may move up and down within the sleeve 137. The valve member 139 is carried by and extends through the upper enlarged end of the sleeve 137. A circular spring member 138 positioned within the upper enlarged end of the sleeve 137 resiliently holds the valve member 139 outwardly and so resiliently presses it against the inside face of the air outlet plug 141. The contacting faces, respectively, of the valve member 139 and the outlet plug 141 are ground flat to form a good seal connection between them so that the valve 139 acts as a valve for the air outlet opening 140. When the valve member 139 is moved up in proper alignment so as to block the outlet opening 140, then communication between the interior of the fluid chamber and the atmosphere is prevented. Upon the valve member 139 being moved downwardly away from the outlet opening 140, then communication is established between the atmosphere and the interior of the fluid chamber through the outlet opening 140.

There is secured to the lower end of the sleeve 137 a drag member 142 which has a flange fitting into notches cut into the lower end of the sleeve 137 so that the sleeve 137 and drag member 142 are secured together and move up and down in unison. The drag member 142 has an axial opening through which the plunger 134 extends and is split at its lower end so as to form two halves, one-half on one side of the plunger. 134 70

and the other half on the other side of the plunger 134. The drag member 142 is preferably made of bronze or some other soft metal of suitable nature. There are flange portions 150 extending along the outside of the drag member 142 and extending through the flange portions 150 are four screw bolts 143. Small coil springs 144 are positioned under the heads of the screw bolts 143 so that the mating flange portions are resiliently held towards each other and against the plunger 134 by the springs 144 and the screw bolts 143. Therefore, the split drag member 142 is mounted resiliently to the plunger 134 in such a way that the frictional engagement of the plunger 134 with the drag member 142 carries the drag member 142 up and down with the reciprocal movement of the plunger 134. However, the resiliency of the springs 144 is such that the drag member 142 is not rigidly secured to the plunger 134 and limitation of the movement of the sleeve 137 causes the plunger 134 to slide through the drag member 142 and to continue its reciprocal movement. Therefore, as long as the sleeve 137 is free between its limits of travel, it is carried along by the plunger 134. Upon the sleeve member 137 meeting the limits of its travel, it is stopped thereby, and the plunger 134 is caused to slide with a drag through the drag member 142. There is a shoulder 146 upon the upper end of the sleeve 137 which is adapted to engage the shoulder 147 extending out within the chamber member 133. Therefore, the shoulder 147 upon engaging the shoulder 146 prevents the sleeve 137 from moving downwardly with the plunger 134 beyond the point of engagement. There is a shoulder 148 positioned within the chamber member 133 which is adapted to engage the shoulder 149 of the drag member 142, and prevents the sleeve member 137 from being carried upwardly by the plunger 134 beyond the said point of engagement.

Downward movement of the plunger 134 carries the sleeve 137 and the valve member carried thereby downwardly so that the valve member 139 opens the outlet conduit 140. Upward movement of the plunger 134 carries the sleeve 137 and the valve member 139 carried thereby upwardly to close the outlet conduit 140. At the beginning of each reciprocal movement of the plunger 134, the valve 139 is operated by the dragging action of the drag member 142 and further movement of the valve 139 is prevented until the plunger 134 begins its next reciprocal movement. It is therefore seen that operation of the valve member 139 to open or to close the outlet conduit 140 occurs only during the initial portion of the upward or of the downward movement of the plunger 134.

A partition 145 extends part way up through the open space within the chamber member 133 so as to partially divide the said open space. Extending down into the open space constituting the fluid chamber within the chamber member 133 is positioned the pipe 132 threadably secured at its upper end to the casing member 125. Fluid drawn up through the pump housing follows a tortuous path and flows through the sleeve 137 and overflows in the chamber member 133 and around the partition 145 and up into the pipe 132. The outlet conduit 128 is formed within the casing member 125 and extends through the wall thereof so as to provide communication between the fluid chamber within the chamber member 133 with the hose connection 124, to which the hose conducting fluid to the part to be lubricated

is attached. There is a check valve 130 positioned in the path of the fluid flowing through the outlet conduit 128 for the purpose of providing a resistance to the flow of the fluid and preventing air after the pump is in operation from entering the tube 132 and causing said air to be entrapped in the uppermost part of the chamber 133 and there vented through the opening 140. A by-pass valve 131 is provided to permit fluid to flow back into the outlet conduit 128 around the check valve 130 in the event that excessive pressure is generated in the hose such as may be caused by the expansion of the fluid under the heat of the sun upon the hose. In the event that there is considerable back pressure of the fluid from the hose attached to the pump housing so as to cause an excessive amount of pressure within the pump housing, there is provided a very small pin hole 165 in the check valve 162. The continuance of the excess pressure permits the fluid entrapped by the check valve 162 to slowly leak out through the small pin hole 165 and thus permitting the piston 154 and plunger 134 to move downwardly through the pump cylinder. This downward movement caused by the excessive back pressure will, by moving the sleeve 137 downwardly, open up the valve 139 and thus permit fluid to escape through the conduit 140, which thus acts as a safety valve to release the excessive pressure within the pump housing.

The fluid chamber within the chamber member 133 is sealed from the air cylinder of the air motor by the illustrated chevron seals. The upper chevrons and coil spring are held down in place by the threaded plug 85 and the lower chevrons and coil spring are held up into proper position by the threaded plug 129. There are two small openings 126 and 127 extending through the wall of the casing member 125 for permitting any fluid which may leak up past the lower chevron seals to escape from the casing member. Any fluid which may escape beyond the lower chevrons may seep out through the small opening 127. Should any more fluid work up past the opening 127 beyond the chevron seal, then it may escape out through the small opening 126. In this way there is an effective seal to prevent fluid from working up along the plunger 79 into the air cylinder of the air motor.

In operation, fluid is drawn up through the inlet opening 164 by the pumping action of the upwardly moving piston 154, the junction 157 which constitutes a valve being closed during this movement. The fluid which is drawn in the lower end of the pump cylinder 152 is entrapped therein by the valve 162. Also, during the upward movement of the piston 154, the fluid in the pump cylinder 152 which is above the piston is forced upwardly in the pump cylinder 152 and the travel or path of flow of the fluid is as follows: From the upper end of the pump cylinder 152, beginning at the bottom of Figure 1, fluid flows into the annular space between the outside of the plunger 134 and the inside of the sleeve 137. The fluid rises in this annular space, until it overflows the top edge of the sleeve 137 and then it flows down into the well defined by the partition 145 in the bottom of the chamber 133, after which it is forced upwardly through the depending tube 132 therein and thence into the outlet conduit 128. On downward movement of the piston 154, the juncture 157 is open with the result that the piston 154 and the head 158 are merely displaced in the fluid, thereby causing the

fluid in the pump cylinder 152 which is below the piston 154 to flow through the open junction 157 into the pump cylinder 152 above the piston 154. Upon the upward movement of the piston the cycle is completed. The repeated raising of the piston 154 draws fluid up into the fluid chamber within the chamber member 133. The fluid upon being continuously pumped flows down around the partition 145 and up through the pipe 132 from whence it is discharged through the outlet conduit 128. Any air liberated from the fluid collects at the top of the fluid chamber. The arrangement of the pipe 132 within the fluid chamber of the chamber member 133 acts to entrap the air liberated from the fluid so that an air pocket is formed in the uppermost part of the chamber. The downward movement of the plunger 134 operates the valve member 139 to permit the air so entrapped to escape out through the air outlet conduit 140 to atmosphere. The downward movement of the plunger 79 into the fluid in the fluid chamber displaces fluid contained therein and the displacement of fluid by the downward movement of the plunger 79 also causes the displaced fluid to compress the entrapped air and to expel it out through the conduit 140 opened by the valve member 139. Therefore when there is entrapped air pocketed in the top of the fluid chamber the downward movement of the plunger 79 aids in the expelling of the entrapped air to the outside of the casing member 135.

Upon the upward movement of the plungers 79 and 134, the valve 139 closes the conduit 140 so that fluid raised up into the fluid chamber under pressure by the upward movement of the plungers is not permitted to escape out through the conduit 140, but is caused to flow out through the outlet conduit 128.

Upon downward movement, the disengagement of the piston 154 with the head 158 opens the openings 151 and permits the plunger 134 and the piston 154 carried thereby to be displaced downwardly through the fluid entrapped within the pump cylinder by the check valve 162. Thus fluid is expelled through the opening 128 only upon the upward movement of the piston.

Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

1. A fluid pumping device comprising, in combination, cylindrical means, piston means reciprocally mounted in the cylindrical means, means for causing the piston means to draw fluid into the cylindrical means, said cylindrical means having a fluid outlet through which fluid is expelled upon a movement of the piston means in one direction, said cylindrical means also having an air pocket at a higher level than the fluid outlet to entrap air liberated from the fluid, means to vent said air pocket, and means mechanically connected to, and responsive to the movement of, the piston means in the opposite direction to positively open said vent means by said movement and to allow the entrapped air to escape, said piston means displacing fluid in the air pocket in the upper level of said cylindrical means to force entrapped air therefrom.

2. In combination, a pump housing having an

inlet and an outlet, a plunger reciprocally movable in said housing, a pump piston slidably mounted in said housing and operable by said plunger, said pump piston being adapted to pump fluid through said housing from the inlet to said outlet, the said housing having an air trap arranged within said housing to trap air liberated from the fluid in said housing, said housing having a discharge vent adapted to communicate with said air trap, valve operating means carried by the plunger, and valve means connected to said valve operating means and operable by the reciprocal movement of the said valve operating means carried by the plunger for controlling the communication between the air trap and the discharge vent and arranged to positively close the discharge vent upon upward movement of the plunger and to open the discharge vent upon downward movement of the plunger to permit air in said air trap to escape through the discharge vent.

3. In combination, a pump housing having an inlet and an outlet, a plunger reciprocally movable in said housing, pump means operable by said plunger for pumping fluid through the housing from said inlet to said outlet, said housing having a fluid chamber through which said plunger extends, said fluid chamber having an air trap in its upper portion for collecting liberated air from said fluid, and means operable by the said plunger for releasing air from said air trap upon downward movement of said plunger in the fluid chamber, said plunger upon downward movement in the fluid chamber providing a displacement therein to force air from said air trap.

4. In combination, a pump housing having an inlet and an outlet, a plunger reciprocally movable in said housing, a piston carried by said plunger for pumping fluid through the housing from the inlet to the outlet by the upward movement of the said plunger, said housing having a fluid chamber through which said plunger extends, said fluid chamber having an air trap in an upper portion thereof through which the plunger extends for the collection of air liberated from the fluid in said chamber, and discharge means mechanically connected to, and directly operable by the downward movement of, said plunger for releasing said air in the air trap, the downward movement of the plunger displacing fluid in said fluid chamber upon operation of the discharge means, the displaced fluid forcing said air out of the air trap through said discharge means.

5. In combination, a liquid pump housing having a movable piston therein, air discharge means for releasing from the pump housing entrapped air displaced by said piston and liberated by the liquid being pumped from the pump housing, and friction means mechanically connected to, and

directly operable by the movements of, the piston for actuating the air discharge means, means for limiting the movement of the air discharge means to a value which is less than the movement of the piston, said friction means after actuating the air discharge means having relative movement with respect to the piston.

6. In combination, a liquid pump housing having a movable piston therein, air discharge means for releasing entrapped air liberated by the liquid being pumped from the pump housing, and friction means operable by the movements of the piston for mechanically actuating the air discharge means during the initial phases of said movements of the piston.

7. The combination with a liquid pump having a movable piston therein, of air discharge means for releasing from the upper portion of the pump entrapped air liberated by the liquid being pumped from the pump, and friction means mechanically operable by the piston for positively actuating the air discharge means, means for limiting the movement of the air discharge means to a value which is less than the movement of the piston, said friction means after actuating the air discharge means having relative movement with respect to the piston.

8. The combination with a liquid pump having a movable piston therein, of air discharge means for releasing entrapped air liberated by the liquid being pumped from the pump, and friction means mechanically operable by the piston for actuating the air discharge means during the initial phases of movement of said piston.

9. In combination, a pump housing, a piston mounted therein, said housing and piston being relatively movable with respect to each other for pumping material, air discharge means for releasing entrapped air liberated by the material being pumped from the pump housing, and friction means operable in accordance with the relative movement of the pump housing and the piston for mechanically actuating the air discharge means during the initial phases of said relative movement.

10. In combination, a pump housing, a piston mounted therein, said housing and piston being relatively movable with respect to each other for pumping material, air discharge means for releasing entrapped air liberated by the material being pumped from the pump housing, and friction means operable in accordance with the relative movement of the pump housing and the piston for mechanically actuating the air discharge means, means for limiting the movement of the air discharge means to a value which is less than the said relative movement, said friction means slipping after actuating the discharge means to the limit of its movement.

JAMES J. PELOUCH.
